CLAIM

The ornamental design for a bottle, as shown and described.

DESCRIPTION

FIG. 1 is a perspective view a first preferred embodiment of the bottle;

FIG. 2 is a front elevation view of the first preferred embodiment thereof;

FIG. 3 is a rear elevation view of the first preferred embodiment thereof;

FIG. 4 is an elevation view of the left side of the first preferred embodiment thereof;

FIG. 5 is an elevation view of the right side of the first preferred embodiment thereof;

FIG. 6 is a top plan view of the first preferred embodiment thereof;

FIG. 7 is a bottom plan view of the first preferred embodiment thereof;

FIG. 8 is a perspective view of a second preferred embodiment of the bottle;

FIG. 9 is a front elevation view of the second preferred embodiment thereof;

FIG. 10 is a rear elevation view of the second preferred embodiment thereof;

FIG. 11 is an elevation view of the left side of the second preferred embodiment thereof;

FIG. 12 is an elevation view of the right side of the second preferred embodiment thereof;

FIG. 13 is a top plan view of the second preferred embodiment thereof; and,

FIG. 14 is a bottom plan view of the second preferred embodiment thereof.

The broken lines shown illustrate portions of the bottle that form no part of the claimed design.
